UNITED STATES PATENT OFFICE.

WILLIAM KNAPP, OF CHANUTE, KANSAS.

STILL-CLEANING DEVICE.

Application filed October 7, 1922, Serial No. 593,004. Renewed July 3, 1926.

This invention relates to a vacuum oil still, and the object of the invention is the provision of a simple and efficient brushing apparatus for brushing the interior of the still. 5

Another object of the invention is the construction of simple and efficient drip plates to be used in a separator power tank.

A further object of the invention is an improvement of the construction of a vacuum oil still, involving a still with a dome, a vacuum pump connected to said dome, together with a separator power tank and condenser coils connected to the vacuum pump and still. 10

With these and other objects in view, my invention comprises certain novel combinations, constructions and arrangements of parts as will be hereinafter described, illustrated in the accompanying drawings, and more particularly pointed out in the appended claim. 15

In the drawings:

Figure 1 is a view in elevation, partly shown in section (and partly shown in side elevation) of an apparatus constructed in accordance with the present invention, while 20

Figure 2 is a top plan view of the same.

Figure 3 is a sectional view, taken on line 25 3—3, Fig. 1, and looking in the direction of the arrows.

Figure 4 is a sectional view, taken on line 4—4, Fig. 1, and looking in the direction of the arrows.

Figure 5 is a sectional view, taken on line 35 5—5, Fig. 1, and looking in the direction of the arrows.

Figure 6 is a plan view of a blank from which a finished drip plate is formed.

Figure 7 is a perspective view of the 40 brushing device.

Figure 8 is a sectional view, taken on line 8—8, Fig. 7, and looking in the direction of the arrows.

Referring to the drawings by numerals, 45 1 designates the furnace of the apparatus, 2 is the still and 3 is the dome of said still. An engine 4 is positioned contiguous to the furnace 1.

A platform 5 supports the vacuum pump 6, and supported upon the platform 5 is the separator power tank 7. A water box 8 is formed upon the platform 5 and within said box are condenser coils 9. A vapor line 10 connects the vacuum pump to the top of dome 3. A pipe 11 connects the tank 7 to

pump 6. A light vapor line 12 connects the condenser coils with the top of tank 7. A back trap line 13 is connected at one end to the condenser coils, and its other end enters 60 the still 2, opening near the bottom portion of the still.

A thermometer 14 is placed on the still 2.

A brushing device 15 is positioned in still 2 and comprises a horizontal shaft 16, a 65 handle 17, rods 18 and brushes 19, Fig. 7. On each brush 19 are formed integral, heads 20 into which the lower ends of the rods are threaded; the upper ends of the rods are threaded into depending extensions 21, 70 formed upon the shaft 16. From an inspection of Figure 8 it will be seen that the upper and lower ends of the rods 18 are oppositely threaded and that turning of the rods will therefore adjust the brushes radially 75 within the still 2, so that the bristles of the brushes can properly engage the inner face of the tank, at all times, for efficiently brushing the same.

A connecting shaft 22 connects the engine 80 4 with the handle 17, so that when the engine is running, the shaft 16 will be operated for causing the brushes to brush the still.

The drip plates 23 are each formed from 85 a single piece of metal and provided with apertured ears 24, which are turned down so that they will engage the inner face of tank 7. Suitable fastening means extend through the ears 24 and tank 7, fastening the drip plates in a staggered or alternating, 90 inclined position, as clearly shown in Fig. 1.

It is to be noted that my brushing device will brush or scrape the bottom of the still, keeping all sediment from settling, and the brushing device will also agitate the contents of the still. I preferably construct the brushes of steel, both the back of the brushes as well as the bristles. 95

Any standard form of a vacuum pump 6 may be used but I claim it to be novel to connect the vacuum pump through the vapor line 10 direct to the top of the dome 3. The construction of my drip plates 23, in a low vacuum still, will increase the output of gasoline from 10% to 20% by returning the 100 heavy vapor through the valve 25 and line 13 to the still 2 where it has an opportunity of further cracking. Without my plates 23, the heavy vapors will be carried over with the "light" through line 12. In the running of heavy oils the valve 25 will be closed and the heavy vapors will run through valve 26, 105 110

and condenser coils 9, while the light vapor will still go through the condenser coils 9 and line 12.

The valved line 27 may be used for charging the pump.

While I have described the preferred embodiment of my invention, and have illustrated the same in the accompanying drawings, certain minor changes or alterations 10 may appear to one skilled in the art to which this invention relates, during the extensive manufacture of the same and I, therefore, reserve the right to make such alterations or changes as shall fairly fall within 15 in the scope of the appended claim.

What I claim is:

In an apparatus of the class described, a cylindrical still having heads provided with bearings, a rotary shaft extending axially

of said still and journaled in the bearings 20 of said heads and, having one end portion extending externally of the still, internally threaded socket arms extending radially from said shaft, cleaning members disposed within said still and extending longitudinally of the still and shaft and each having a back provided with internally threaded sockets aligned with socket arms of the shaft, and connecting rods extending radially of the shaft and having their end portions threaded and screwed into the sockets of the cleaners and socket arms of the shaft whereby upon rotation of the shaft the cleaners will be swung about the still in cleaning engagement with the walls thereof. 30 35

In testimony whereof I hereunto affix my signature.

WILLIAM KNAPP.
